UNITED STATES PATENT OFFICE.

JOSEPH M. LUCARELLE AND VICTOR L. FRYKMAN, OF BRIDGEPORT, CONNECTICUT, AS
SIGNORS TO DICTAPHONE CORPORATION, OF BRIDGEPORT, CONNECTICUT, A COR-
PORATION OF NEW YORK.

RECORD-RESURFACING MACHINE.

Application filed April 27, 1927. Serial No. 187,094.

This invention relates to record-resurfacing machines, and more particularly to an improved machine for shaving record-blanks, particularly those intended for use 5 with dictation machines.

An object of the present invention is to provide means for facilitating the setting of the record-engaging tool—a knife, for instance.

10 Another object of the present invention is to provide means for automatically advancing the knife to take a second or finishing cut after the first or rough cut has been taken.

15 And a still further object of the present invention is to provide means for automatically releasing the knife from set position when the shaved record is to be removed from the machine.

20 An important feature of the present invention, which will appear more fully in the specific description of the machine shown in the accompanying drawings, is the provision of means for gauging the depth of cut, which 25 means is so arranged that it is not liable to damage the finished surface of the record.

Another important feature is the provision of means for automatically advancing the knife a predetermined amount when the 30 knife carriage is moved to return it to position to start shaving a record.

Another important feature of the present invention is the provision of means for returning the knife to normal unset position 35 when a gate for holding the record mandrel shaft in operative position is opened preparatory to the removal of the record from the mandrel.

Other features and advantages will herein- 40 after appear.

In the accompanying drawings which illustrate one form of the invention, that at present preferred—

Figure 1 is a top plan view of a record 45 shaving machine made in accordance with the present invention, the record shaving knife being in the position it usually assumes before the knife-bar carriage is moved to position to start the cutting of a record.

50 Fig. 2 is a side view of the operating parts of the present invention, showing the frame and part of the knife-bar carriage in section.

Fig. 3 is a rear view of the knife-bar car-

riage, showing the means for adjusting the knife for a second or finishing cut and the 55 means for releasing the knife-bar at the proper time.

Fig. 4 is a view of part of the knife-bar carriage, showing the means for automatically releasing the knife-bar from set position. 60

Fig. 5 is a sectional view taken through the line 5—5 of Fig. 2, and showing the operating parts of the present invention.

Fig. 6 is a sectional view through the 65 knife-bar carriage taken on the line 6—6 of Fig. 4, and showing the means for locking the knife-bar in adjusted position.

Fig. 7 is a detail view showing the operative connection between the end gate for 70 holding the mandrel shaft and the means for releasing the knife-bar from set position when the end gate is open.

The shaving machine shown in the accompanying drawings is particularly adapted 75 for shaving or otherwise resurfacing phonograph record blanks, particularly those adapted to be used with dictation machines. It comprises a frame base 10 provided with a left-hand standard 11 and right-hand 80 standards 12 and 13. Supported between the standards 11 and 12 is a guide-rod 14 adapted to receive a bearing sleeve 15 of a knife-bar carriage 16, whose forward end is provided with a shoe 17 adapted to ride 85 on a rail 18 forming part of the frame 10. The knife-bar carriage 16 extends forwardly and upwardly from the sleeve 15 to a point above the rail 18 where it is provided with a ball-shaped weight and hand-piece 19 and 90 from the latter it continues downwardly to the shoe portion 17.

Located in front of the guide-rod 14 and bearing at one end on a pivot screw 20 carried by the standard 11, is a mandrel shaft 95 21 carrying a driving pulley 22 and a mandrel 23. At its end opposite the pulley 22, the mandrel shaft 21 is supported by a pivot screw 24 carried by a gate 25 secured to a shaft or stud 26 rotatably mounted in the frame 10 at 27. The gate 25 is locked in operative position, firmly engaging the standard 13, by a manually releasable spring- 100 catch 28 and is provided at its front end with a finger-piece 29 by means of which it 105 is operated. When the gate 25 is opened,

the mandrel shaft rests on a lug 30 on the frame 10, and free movement of the mandrel and mandrel shaft to the right, as viewed in Fig. 1, is prevented by a collar 31 carried by the mandrel shaft.

After a record 32 is placed on the mandrel 23 as shown in Fig. 1, the operator grasps the handle 29 and swings the gate on its shaft 26 until the gate engages the standard 13, at which time the pivot screw 24 enters a companion hole in the end of the mandrel shaft 21 and raises the mandrel shaft to operating position. The spring-catch 28 is then moved to locking position by means of 15 a finger-piece 33 provided thereon.

With the record mounted on the mandrel and the gate 25 closed as above described, the record is in position to be shaved as the result of the movement of the knife-bar 20 carriage 16 longitudinally of the record under the influence of a feed-screw 34 mounted between standard 35 and standard 11 and engaged by a feed nut 35 carried by a spring-arm 36 mounted on the sleeve 15 of 25 the knife-bar carriage 16. The feed-screw 34 is caused to operate coordinately with the mandrel shaft 21 by means of a connecting belt 37 engaging a pulley 38 on the feed-screw shaft 34 and a pulley 39 carried by the 30 mandrel 21 alongside of the pulley 22. The pulley 22 is driven from a suitable source of power, such as an electric motor not shown, by means of a belt 40 engaged thereon.

The above described structure and mechanism are common to record-resurfacing machines heretofore manufactured and used, and form a part of the present invention only in so far as they are related to or combined with other mechanism hereinafter described.

Phonograph record blanks are customarily shaved to resurface them for use when it is desired to obliterate a record preparatory to producing a new record on the surface 45 of the blank. But, this operation may also be accomplished by means of burnishing tools and other arrangements. In so far as some of the salient features of the present invention are concerned, it is immaterial whether the record-engaging tool is a knife 50 or a burnisher or other device. However, since the method of cutting is the one most frequently used and the most preferable at present, it is illustrated herein.

55 The device illustrated herein has a knife-bar 41 adapted to carry at its end a knife 42 usually made of sapphire or other hard stone. This knife-bar 41 is, as usual, slidably mounted in a housing 43 forming part 60 of the knife-bar carriage 15 and is adapted to be moved so as to bring the knife 42 into contact with the record surface so that rotation of the record and travel of the knife with the knife-bar carriage 16 causes the top 65 surface of the record to be removed. The

knife is preferably provided with a chip-chute 44 into which the shavings from the record pass when removed from the record-surface and through which they fall downwardly through an opening 45 in the frame 70 10 to a suitable container, (not shown) provided for the purpose.

In order that the knife may be quickly and easily set to proper operating position when taking the first or rough cut in resurfacing a record blank, the present invention provides means whereby the direct manual operation causes the knife-bar to be set in such position that the knife will extend into the record-surface a predetermined 75 extent, so that when the mandrel is rotated there is removed from the record-surface a layer of a predetermined thickness. This means, according to the present invention, comprises a gauge-bar 46 mounted in the 80 housing 43 to slide parallel with the knife-bar 41 and a yoke or tie-bar 47 connecting the gauge-bar 46 with the knife-bar 41 for movement en bloc toward and from the record-surface. The knife-bar 41 and the 85 gauge-bar 46 are so interconnected and formed that the working surface of the knife 42 extends beyond the working surface 48 of the gauge-bar 46 by an amount equal to the depth of cut which it is intended to take with the machine, for example, fifteen ten-thousandths of an inch. Thus, when the knife-bar 41 and gauge 90 46 are moved toward the record by the operator pressing his finger against the button 49 carried by the gauge-bar 46 until the working surface 48 of the gauge-bar engages the record-surface, the knife 42 will be in position to take a cut of predetermined 95 depth from the record blank.

The gauge-bar 46 may, of course, be located at either side of the knife-bar 41 depending upon what point in the operation of the machine it is desired to set the knife-bar. However, according to the present invention, the gauge-bar is set behind the knife-bar, considering the direction of travel of the carriage, so that the gage-bar is always above and spaced from the record-surface while the knife is shaving and does not contact with the finished record-surface. The knife is set relative to the record for the initial cut when the carriage is in the finish position of cutting travel at the left side of the machine as shown in Fig. 1. With the 100 carriage in this position, the operator pushes the gage-bar forwardly toward the record until the gage-bar engages the record and the interconnected knife which is slightly ahead of the gage-bar and is positioned and locked as shown in Fig. 1, but does not dig into the record-surface because it is beyond the end of the record. After this conditioning, the carriage is lifted and then moved 105 to the starting position of travel at the right 110 115 120 125 130

side of the machine after which the carriage regularly advances over the record-surface and the knife takes a cut of predetermined depth while the trailing gage-bar clears the record-surface an amount equivalent to the depth of cut. The amount of space between the gauge-bar and the record-surface depends upon the depth of cut. In the case cited, there will be a fifteen ten-thousandths clearance or more between the gauge-bar and the record-surface when the gauge-bar is, as shown in the drawings, caused to trail the knife-bar. This is a particularly important feature of the present invention, for, by having the gauge-bar trail the knife-bar, the gauge-bar is not in contact with the record, and therefore will not transmit to the knife-bar irregularities or eccentricities which the record may have. Moreover, by having the gauge-bar trail the knife-bar, it can be located in a position to engage the end of a record-blank when the knife-bar carriage 16 is in the position it occupies when the last record-blank was shaved—namely to the left as shown in Fig. 1, in which position the feed-nut 35 has left the threaded portion of the screw-shaft 34 and is over a cut-away portion 34^a thereon. When the carriage is in this position and the gauge-bar 46 is placed behind the knife-bar, the gauge-bar may be spaced sufficiently from the knife-bar longitudinally of the record-blank so that the gauge-bar will be in position to contact with the end of a record-blank while the knife-bar is beyond the end of the record-blank. Hence, the knife-bar gauge may be moved to position by hand as described without pressing or forcing the knife 42 into the record-surface. Preferably, the working surface 48 of the gauge-bar 46 is made so large that the force with which it engages the surface of the record-blank is not sufficient to cause the record-blank to be indented by the gauge-bar. However, if a slight indentation does occur in particularly warm weather or if an abnormally large amount of force is used in setting the knife-bar, it will not result in damage being done to the finished record-surface, but will merely cause the knife-bar to be set slightly deeper, any indentations produced being removed by the shaving operation.

As may best be seen in Figs. 5, 6 and 4, the knife-bar 41 is locked in the position determined by contact of the gauge 46 with the record by means of a clamping arm 50 mounted on a screw 51 supported by the housing 43 and normally forced upwardly to position to engage a flattened surface 52 on the knife-bar by means of a spring 53 secured to the housing 43 by a screw 54. The spring 53 is made strong enough so that the clamping arm 50 will bear against the knife-bar 41 and force the same against a sleeve 55 mounted in the housing 43 to hold the

knife-bar and the sleeve against movement in the housing except when the sleeve itself is moved as will hereinafter appear.

In order to release the clamping arm 50 when it is desired to adjust the knife-bar to position to take the first or rough cut, it is provided with a releasing lever 56, (Figs. 3, 4 and 6) pivoted on a screw 57 mounted in the housing 43, and this lever is provided with a cam surface 58 adapted to engage the end 59 of the clamping arm 50 and depress the same to move it away from the knife-bar 41 when the lever is moved forwardly in the direction of the arrow shown in Fig. 4.

Thus, to set the knife 42 in position to take a predetermined cut from the record-surface, the releasing lever 56 is first pulled forwardly and then the finger-piece 49 on the gauge-bar 46 is pushed forwardly to cause the working surface 48 to engage the record and then the releasing lever 56 is returned to locking position shown in Fig. 4.

As stated above, the present invention provides means for automatically advancing the knife-bar and knife to take a second or finishing cut as an incident to the movement of the knife-bar carriage to position to take that cut. This means, according to the embodiment of the invention herein disclosed, comprises an arrangement for moving the sleeve 55 (which as stated is interposed between the knife-bar 41 and the housing 43) a predetermined amount each time that the knife-bar carriage 15 is swung upwardly and rearwardly from the position shown in Fig. 1, which movement it is necessary to give to the carriage 15 so as to release the feed-nut 35 from the feed-screw 34 and thereby permit the carriage 15 to be returned to the right to start shaving the record. The movement of the sleeve 55 is accomplished by the present invention by cooperating cam surfaces 60 and 61 (see Fig. 5), the former being provided on the sleeve 55 and the latter being provided on a disk 62 mounted to rotate on the end of the knife-bar 41. As may best be seen in Fig. 3, the disk 62 is provided with a segment 63 having ratchet teeth 64 thereon adapted to be engaged by a pawl 65 carried by an arm 66 pivotally mounted on a screw 67 secured in the housing 43, a spring 68 being connected to the pawl 65 so as to hold the pawl and its operating arm 66 normally in inoperative position. When the pawl arm 66 is raised from the position shown in Fig. 3, the pawl 65 is forced against the ratchet teeth 64 of the segment 63 to turn the segment 63 one step. This causes the cam 61 to rotate and force the sleeve 55 forwardly in the housing 43 an amount sufficient to advance the knife to take a finishing or second cut.

The movement of the knife-bar 41 for-

wardly with the sleeve 55 is possible, because the clamping arm 50 which engages it and the knife-bar may also move forwardly with the sleeve, the clamping arm bearing 5 surface 69 on the screw being long enough to permit the clamping arm 50 to slide forwardly on it against the tension of a spring 70 interposed between the head of the screw 51 and the clamping lever 50. During this 10 movement, the clamping arm 50 still maintains the knife-bar 41 clamped in the desired adjusted position with relation to the sleeve. Since the sleeve 55 has a cut-away portion 70^a embracing the arm 50 and the 15 arm 50 is normally urged backwardly by the spring 70, this spring also keeps the cam surface 60 on the sleeve 55 firmly pressed against the cam surface 61 on the collar 62 and returns the same to its rearmost position 20 when such action is otherwise permitted.

Occasionally, the second and so-called finishing cut is not sufficient to entirely remove the grooves produced on the record by 25 the last recording operation, and hence it is desirable to take one or more extra finishing cuts. In order to permit this to be done without requiring a readjustment of the setting of the knife by operating the releasing 30 lever 56 and resetting the knife and the gauge 46, the segment 63 is provided with enough teeth 64, and the cam surfaces 60 and 61 are shaped to accommodate the largest 35 number of secondary cuts, (five in the case shown) that the machine would ever be required to make.

In order that the machine may always be 40 in position to take a finishing cut, the segment 63 and its cam 62 are returned to normal position, shown in Fig. 5, each time the release lever 56 is operated to release the clamping arm 50 and allow the knife-bar 41 and gauge-bar 46 to be returned to normal position by a spring 71, see Fig. 5. As 45 may be seen in Figs. 4 and 3, this is accomplished by providing a link 72 connected to the releasing lever 56 at 73 with a rearwardly extending arm 74 located in position to engage an arm 75 carried by the segment 50 63 on the side opposite that having the teeth 64. When the releasing lever 56 is swung forwardly, the arm 74 thereon engages the arm 75 on the segment 63 and moves the same upwardly, the arm 74 thereon 55 engages the arm 75 on the segment 63 and moves the same upwardly until further movement is arrested by the engagement of the arm 75 with the rear end of the gauge-bar 46.

60 Attention is here called to the fact that any backward thrust produced by the record on the knife-bar 41 or gauge 48 is absorbed by a plate 76 (see Figs. 3, 4 and 5) which is secured to the housing 43 by screws 77. The 65 cam disk 62, which takes the backward

thrust through the sleeve 55, bears against the plate 76 through the intermediary of a washer 62^a interposed between the disk 62 and the plate. The knife-bar is advanced, as above described, automatically each time 70 the carriage is raised to return it while in the position shown in Fig. 1 by means of a plunger 78 whose upper end engages a pawl arm 66 and whose lower end is adapted to lie in a socket 79 provided in the guide rail 75 14 (as shown in Fig. 3). When the carriage 15 is in a position where the plunger 78 lies in the socket 79 and the carriage 15 is swung upwardly and rearwardly by the operator grasping the handle 19, the plunger 78 rides 80 up on a cam surface 80 of the socket 79 and causes the pawl arm 76 to be raised and the pawl 65 to advance the segment 63 an extent equal to the length of one tooth. While the carriage is in this elevated position, it is 85 moved longitudinally of the record to bring it to the right-hand side of the machine as viewed in Fig. 1, whereupon it is let down to bring the knife 42 into position to engage the record-surface. During this return 90 movement and subsequent traveling movement of the carriage 15, the plunger 78 is maintained elevated because it rides on the cylindrical surface of the guide rod 14. When, however, the end of the cutting operation is approached, the plunger 78 drops 95 into the socket 79 and is then in position to cause the pawl 65 to advance the segment 63 one tooth when it is again raised to return it for another finishing cut, if such is 100 found to be necessary.

It will be seen from the above that the setting of the knife 42 is controlled not only by the gauge-bar 46 but also by the cooperating cam surfaces 60 and 61, the latter being 105 controlled by the segment 63, and it will also be noted in the construction described that even immediately after the knife-bar is set by hand to determine the depth of cut by means of the gauge 46, it is advanced an 110 amount equal to a secondary cut by the segment 63 when the carriage is raised to return it to position to start shaving the record. This advance of the knife which is desired for secondary cut is taken into consideration and compensated for by making the gauge-bar 46 that much longer. For instance, if it is desired to take a rough or first cut of twenty thousandths of an inch, and the secondary adjusting means comprising the cams 60 and 61 and the segment 63 are set to advance the knife-bar five thousandths of an inch for each increment movement of the cam 61 by the ratchet pawl 65, the knife 42 is set only fifteen thousandths 115 of an inch in advance of the working face 48 of the gauge-bar 46. Hence, when it is first set by hand, the knife will be in a position to remove a layer of record material fifteen thousandths of an inch thick. How- 120 125 130

ever, when the carriage 15 is raised to return it in position to take the rough cut, it will have been automatically adjusted five thousandths of an inch more so that it will 5 actually take a cut of twenty thousandths of an inch deep.

As stated above, the releasing lever 56 may be moved by hand to release the clamping arm 50 so that the knife-bar 41 and 10 gauge-bar 46 may be returned to normal inoperative position by the spring 71. In order to guard against an attempt to remove the record from the mandrel before the knife-bar is released, the present invention 15 provides means connected to the gate 25 for automatically moving the releasing lever 56 to released position as the gate is being opened preparatory to removing the record. This means, as shown in Figs. 3, 4 20 and 7, comprises a cam 80 secured to the shaft 26 to which the gate 25 is also secured. This cam cooperates with a link 81 having a slot 82 riding on a pin 83 carried by a lug 84 extending downwardly from the under- 25 side of the base 10. The link 81 has a follower portion 85 at the end adjacent the cam 80 and a pivotal connection 86 at the other end with a bell crank 87 pivoted to the under side of the frame base 10 at 88 and 30 having an arm 89 adapted to engage a plunger 90 located at the left-hand side of the machine. When the carriage is positioned at the end of its travel after a shaving operation, this plunger 90 underlies an arm 35 91 on the link 72 which, as stated above, is connected by a pin 73 to the release lever 56.

Thus, when the gate 25 is swung open to permit the record to be removed from the mandrel, the cam 80 moves the link 81 to 40 the left, as seen in Fig. 7, and this causes the bell-crank arm 89 to raise the plunger 90, which in turn moves the link 72 upwardly and swings releasing lever 56 which unlocks the knife-bar and permits its return by 45 spring 71 and sets the segment 63 back to starting position.

It should be understood that the plunger 90 is located in a position where it will lie directly beneath the link 72 when the carriage 15 is in its stopping position at the 50 end of a cutting operation—namely, the position shown in Fig. 1, from which position the knife-bar is set for a new first cut or a secondary or finishing cut.

55 Variations and modifications may be made within the scope of this invention and portions of the improvements may be used without others.

Having now described the invention, what 60 is claimed as new and for which it is desired to obtain Letters-Patent, is:—

1. In a record-resurfacing machine, the combination of a mandrel for supporting a record to be resurfaced; a carriage; a record-engaging tool on the carriage; and a 65 record-engaging tool on the carriage; and a

gauge to predetermine the operative position of the record-engaging tool with relation to the record, said gauge being carried by the carriage on the side thereof behind the record-engaging tool in the direction of 70 travel of the carriage when resurfacing a record, and means for causing the gauge to remain in set position during the record resurfacing operation.

2. In a record-resurfacing machine, the 75 combination of a mandrel for supporting a record to be resurfaced; a carriage; a record-engaging tool on the carriage and a gage connected with said record-engaging tool to set the latter for its initial cut; means 80 for causing said gauge to remain in set position during the record resurfacing operation; and means operable while the carriage is located at the end of its travel after resurfacing a record for advancing the record- 85 engaging tool to position to take a finishing cut of predetermined depth.

3. In a record-resurfacing machine, the 90 combination of a mandrel for supporting a record to be resurfaced; a carriage; a record-engaging tool on the carriage and a gage connected with said record-engaging tool to set the latter for its initial cut; means 95 for causing said gauge to remain in set position during the record resurfacing operation; and means automatically operated as an incident to the movement of the carriage to position to start resurfacing the record for advancing the record-engaging tool to position to take a finishing cut of predetermined 100 depth.

4. In a record-resurfacing machine, the combination of a mandrel for supporting a record to be resurfaced; a carriage; a record-engaging tool on the carriage; a gauge 105 manually controlled means for moving the record-engaging tool and gauge to a predetermined operative position with relation to the record carried by said mandrel; means for maintaining said gauge in set position; and means automatically operated as an incident to the movement of the carriage to position to start resurfacing the record for advancing the record-engaging tool a predetermined extent. 115

5. In a record-resurfacing machine, the combination of a mandrel for supporting a record to be resurfaced; a carriage; a record-engaging tool on the carriage; a gauge to predetermine the operative position of the record-engaging tool with relation to the record; manually operated means for moving the gauge and record-engaging tool to operative position with the gauge in contact with the record; means for maintaining the said gauge and record-engaging tool in set position, and means operable while the carriage is located at the end of its travel after resurfacing a record for advancing the record-engaging tool from said predeter- 120 125 130

mined operative position to position to take a finishing cut of predetermined depth.

6. In a record-resurfacing machine, the combination of means for supporting a record to be resurfaced; a record-engaging tool; means for setting the tool in operative position with relation to a record; and means operative automatically as an incident to the operation of removing the record 10 from the machine for returning the set tool to inoperative position.

7. In a record-resurfacing machine, the combination of a mandrel for supporting a record to be resurfaced; a record-engaging 15 tool; means for setting the tool in operative position with relation to a record supported by a mandrel; a lever operated as an incident to the removal of the record from the mandrel; and means controlled by said 20 lever for returning the set tool to inoperative position.

8. In a record-resurfacing machine, the combination of a mandrel for supporting a record to be resurfaced; a record-engaging 25 tool; means for setting the tool in operative position with relation to a record supported by a mandrel; an end gate for the mandrel adapted to be moved to permit the record to be removed from the mandrel; and means 30 controlled by movement of the end gate for returning the set tool to inoperative position.

9. In a record-resurfacing machine, the combination of a mandrel for supporting a record to be resurfaced; a record-engaging 35 tool; means for setting the tool in operative position with relation to a record supported by a mandrel comprising a lock; means for returning the tool to inoperative position with relation to the record when said lock is 40 released; and means operated as an incident to the operation of removing the record from the mandrel for releasing said lock to cause the return of the tool to inoperative position.

10. In a record-resurfacing machine, the combination of a mandrel for supporting a record to be resurfaced; a record-engaging 45 tool; means for setting the tool in operative position with relation to a record supported by the mandrel comprising a lock; means for 50 returning the tool to inoperative position with relation to a record when said lock is released; an end gate for said mandrel adapted to be swung to inoperative position to permit removal of the record from the 55 mandrel; and means operated by movement of said end gate for releasing said lock to cause the return of the tool to inoperative position.

11. In a record-resurfacing machine, the combination of a mandrel for supporting a record to be resurfaced; a carriage; a record-engaging 60 tool on the carriage; means for setting the tool in operative position with relation to a record supported by the mandrel; and means operative when the carriage 65

is in a predetermined position and as an incident to the operation of removing the record from the mandrel for returning the set tool to inoperative position.

12. In a record-resurfacing machine, the combination of a mandrel for supporting a record to be resurfaced; a carriage; a record-engaging 70 tool on the carriage; means for setting the tool in operative position with relation to a record supported by the mandrel; an end gate for the mandrel adapted to be moved to inoperative position to permit the removal of the record from the mandrel; and means operative when the carriage is in predetermined position and as a result 80 of the movement of the end gate to inoperative position for returning the set tool to inoperative position with relation to the record.

13. In a record-resurfacing machine, the combination of a mandrel for supporting a record to be resurfaced; a carriage; a record-engaging 85 tool on the carriage; means for setting the tool in operative position with relation to a record supported by the mandrel comprising a lock; means for returning the tool to inoperative position when said 90 lock is released; an end gate for the mandrel adapted to be moved to inoperative position to permit the removal of the record from the mandrel; a lever system operated by said end gate when moved to inoperative position comprising means adapted to be located within range of the carriage when the carriage is in a predetermined position 100 longitudinally of the record; and an interponent between the last-named means and the said lock operative to cause the lock to be released when said linking system is operated as a result of movement of the end gate 105 to inoperative position.

14. In a record-resurfacing machine, the combination of a mandrel for supporting a record to be resurfaced; a carriage; a record-engaging tool movably mounted on the carriage toward and from a record; a gauge 110 movably mounted on the carriage to predetermine the operative position of the record-engaging tool with relation to the record, said gauge being carried by the carriage at 115 one side of the record-engaging tool and being adapted to engage the record-surface when moved to operative position; and means securing the gauge to the record-engaging tool in predetermined fixed relation 120 for simultaneous movement on the carriage toward and from the record.

15. In a record-resurfacing machine, the combination of a mandrel for supporting a record to be resurfaced; a carriage; a knife; a knife-bar slidably mounted on the carriage for movement toward and from a record; a gauge-bar movably mounted on the carriage to predetermine the operative position of the knife and knife-bar with relation to the rec- 130

ord; said gauge-bar being carried by the carriage at one side of the knife-bar and being adapted to engage the record-surface when moved to operative position; and a tie-bar interconnecting the gauge-bar and knife-bar to fix the gauge-bar and knife-bar together for simultaneous movement on the carriage toward and from a record.

16. In a record-resurfacing machine, the combination of a mandrel for supporting a record to be resurfaced; a carriage; a record-engaging tool movably mounted on the carriage toward and from a record; a gauge movably mounted on the carriage to determine the operative position of the record-engaging tool with relation to the record, said gauge being carried by the carriage at one side of the record-engaging tool and being adapted to engage the record-surface when moved to operative position; means securing the gauge with the record-engaging tool in predetermined fixed relation for simultaneous movement on the carriage toward and from a record; and means for locking the record-engaging tool and gauge in operative record-cutting position.

17. In a record-resurfacing machine, the combination of a mandrel for supporting a record to be resurfaced; a carriage; a record-engaging tool movably mounted on the carriage toward and from a record; a gauge movably mounted on the carriage to determine the operative position of the record-engaging tool with relation to the record, said gauge being carried by the carriage at one side of the record-engaging tool and being adapted to engage the record-surface when moved to operative position; means securing the gauge with the record-engaging tool in predetermined fixed relation for simultaneous movement on the carriage toward and from a record; means for locking the record-engaging tool and gauge in operative cutting position; and means for returning said record-engaging tool and gauge to inoperative position with relation to the record when said locking means is released.

18. In a record-resurfacing machine, the combination of a mandrel for supporting a record to be resurfaced; a carriage; a record-engaging tool on the carriage; a gauge associated with said record-engaging tool; manually operable means for setting the record-engaging tool in predetermined operative cutting position for taking a first or rough cut; and means automatically operated in response to movement of the carriage after the first shaving cut has been made for moving the record-engaging tool from said manually set position to advanced position for taking a finishing cut of predetermined depth.

19. In a record-resurfacing machine, the combination of a mandrel for supporting a

record to be resurfaced; a carriage; a knife; a knife-bar on which said knife is mounted; and a knife-bar holder movably mounted on the carriage for movement toward and from the record relative to the carriage, said knife-bar being movable relative to the holder.

20. In a record-resurfacing machine, the combination of a mandrel for supporting a record to be resurfaced; a carriage; a knife; a knife-bar on which said knife is mounted; a knife-bar holder movably mounted on the carriage for movement toward and from the record while the carriage is in operative position; and means for moving the knife-bar relative to the knife-bar holder.

21. In a record-resurfacing machine, the combination of a mandrel for supporting a record to be resurfaced; a carriage; a knife; a knife-bar on which said knife is mounted; a knife-bar holder movably mounted on the carriage for movement toward and from the record while the carriage is in operative position, said knife-bar being movable relative to said knife-bar holder and means for moving the knife-bar holder and knife relative to the carriage.

22. In a record-resurfacing machine, the combination of a mandrel for supporting a record to be resurfaced; a carriage; a knife; a knife-bar on which said knife is mounted; a knife-bar holder movably mounted on the carriage for movement toward and from the record while the carriage is in operative position; means for moving the knife-bar holder and knife relative to the carriage; and means for moving the knife-bar relative to the holder.

23. In a record-resurfacing machine, the combination of a mandrel for supporting a record to be resurfaced; a carriage; a knife; a knife-bar on which said knife is mounted; a knife-bar holder movably mounted on the carriage for movement toward and from the record while the carriage is in operative position; mean for moving the knife-bar holder and knife relative to the carriage; means for moving the knife-bar relative to the holder; and means for locking the knife-bar to the knife-bar holder for simultaneous movement toward and from the record.

24. In a record-resurfacing machine, the combination of a mandrel for supporting a record to be resurfaced; a carriage; a knife; a knife-bar on which said knife is mounted; a knife-bar holder movably mounted on the carriage for movement toward and from the record while the carriage is in operative position; means for moving the knife-bar holder and knife relative to the carriage; means for moving the knife-bar relative to the holder; means for locking the knife-bar to the knife-bar holder for simultaneous movement toward and from the record; and

means for moving the holder step-by-step a predetermined amount upon each operation thereof.

25. In a record-resurfacing machine, the combination of a mandrel for supporting a record to be resurfaced; a carriage; a knife; a knife-bar on which the knife is mounted; a knife-bar holder movably mounted on the carriage for movement toward and from the record while the carriage is in operative position; manually operable means for moving the knife-bar relative to the holder; and automatically operated means for moving the knife-bar holder toward and from the record.

26. In a record-resurfacing machine, the combination of a frame; a mandrel on said frame for supporting a record to be resurfaced; a carriage slidably and pivotally mounted on said frame; a record-engaging tool movably mounted on the carriage; means to yieldingly hold the record-engaging tool in desired position; and means operated by a pivotal movement of the carriage for advancing the record-engaging tool relative to the carriage against the action of said yielding holding means.

27. In a record-resurfacing machine, the combination of a frame; a mandrel on said frame for supporting a record to be resurfaced; a carriage slidably and pivotally mounted on said frame; a record-engaging tool movably mounted on the carriage; a gauge interconnected with the record-engaging tool; and a pawl and ratchet mechanism for advancing the record-engaging tool relative to the carriage one step when the carriage is given a pivotal movement on the frame.

40 28. In a record-resurfacing machine, the combination of a frame; a mandrel on said frame for supporting a record to be resurfaced; a carriage slidably and pivotally mounted on said frame; a record-engaging tool on the carriage; and means comprising cooperating cam members for advancing the record-engaging member relative to the carriage when the carriage is given a pivotal movement on the frame.

50 29. In a record-resurfacing machine, the combination of a frame; a mandrel mounted on the frame for supporting a record to be resurfaced; a carriage mounted on the frame for pivotal and sliding movements relative to the frame; a knife; a knife-bar on which said knife is mounted; a knife-bar holder movably mounted on the carriage for movement toward and from the record relative to the carriage; and a pawl and ratchet mechanism for moving the knife-bar holder relative to the carriage to advance its position with relation to the record when the carriage is given a pivotal movement.

30. In a record-resurfacing machine, the

combination of a frame; a mandrel mounted 65 on the frame for supporting a record to be resurfaced; a carriage mounted on the frame for pivotal and sliding movements relative to the frame; a knife; a knife-bar on which said knife is mounted; a knife-bar holder 70 movably mounted on the carriage for movement toward and from the record relative to the carriage; and means comprising co-operating cam members for moving the knife-bar holder to advance it relative to the 75 record when the carriage is given a pivotal movement on said frame.

31. In a record-resurfacing machine, the combination of a frame; a mandrel mounted on the frame for supporting a record to be 80 resurfaced; a carriage mounted on the frame for pivotal and sliding movements relative to the frame; a knife; a knife-bar on which said knife is mounted; a knife-bar holder 85 movably mounted on the carriage for movement toward and from the record relative to the carriage; means comprising cooperating cam members for moving the knife-bar holder to advance it relative to the record when the carriage is given a pivotal movement on said frame; and means for returning 90 said cam members and cooperating mechanism and moving the knife-bar holder to normal predetermined position relative to the carriage.

32. In a record-resurfacing machine, the combination of a mandrel mounted for supporting a record to be resurfaced; a carriage; a knife; a knife-bar on which said knife is mounted; a knife-bar holder movably mounted on the carriage for movement toward and from the record relative to the carriage; a cam mounted on the carriage; a cooperating cam connected to the knife-bar holder; and means comprising a pawl 105 and ratchet mechanism for moving the first-named cam relative to the second-named cam to advance the knife-bar holder relative to the carriage.

33. In a record-resurfacing machine, the combination of a frame; a mandrel mounted on the frame for supporting a record to be resurfaced; a carriage mounted on the frame for pivotal and sliding movements; a knife; a knife-bar on which said knife is mounted; a knife-bar holder 115 movably mounted on the carriage for movement toward and from the record relative to the carriage; a cam mounted on the carriage; a cooperating cam connected to the knife-bar holder; means comprising a pawl and ratchet mechanism for moving the first-named cam relative to the second-named cam to advance the knife-bar holder relative to the carriage; and means on the frame for engaging the pawl 120 and ratchet mechanism for operating the same when the carriage is given a pivotal movement.

34. In a record-resurfacing machine, the combination of a frame; a mandrel mounted on the frame for supporting a record to be resurfaced; a carriage pivotally and slidably mounted on said frame; a knife; a knife-bar on which said knife is movably mounted for adjustment relative thereto; a knife-bar holder movably mounted on the carriage for movement toward and from the record relative to the carriage; means for locking the knife-bar to the knife-bar holder in adjusted position; and means for moving the knife-bar, knife-bar holder and knife-bar locking means relative to the carriage.
35. In a record-resurfacing machine, the combination of a frame; a mandrel mounted on the frame for supporting a record to be resurfaced; a carriage pivotally and slidably mounted on the frame; a knife; a knife-bar on which said knife is mounted; a sleeve mounted in the carriage adapted to carry a knife-bar and permit sliding movement of the knife-bar relative thereto, said sleeve being slidably mounted on the carriage; cooperating cam members between the sleeve and the carriage; a pawl and ratchet mechanism for moving one of said cam members relative to the other to advance said sleeve relative to the carriage; and means mounted on the frame for operating said pawl and ratchet mechanism when the carriage is given a pivotal movement.
36. In a record-resurfacing machine, the combination of a frame; a mandrel mounted on the frame for supporting a record to be resurfaced; a carriage pivotally and slidably mounted on the frame; a knife; a knife-bar on which said knife is mounted; a sleeve mounted in the carriage adapted to carry a knife-bar and permit sliding movement of the knife-bar relative thereto, said sleeve being slidably mounted on the carriage; cooperating cam members between the sleeve and the carriage; a pawl and ratchet mechanism for moving one of said cam members relative to the other to advance said sleeve relative to the carriage; means mounted on the frame for operating said pawl and ratchet mechanism when the carriage is given a pivotal movement; means for locking the knife-bar to the sleeve for simultaneous movement toward and from the carriage; means for releasing said locking means; and means operated by said releasing means for returning said cam members to normal position and permitting the return of the sleeve to a predetermined position with relation to the carriage.
37. In a record-resurfacing machine, the combination of a frame; a mandrel mounted on the frame for supporting a record to be resurfaced; a carriage pivotally and slidably mounted on the frame; a knife; a knife-bar on which said knife is mounted; a sleeve mounted in the carriage adapted to carry a knife-bar and permit sliding movement of the knife-bar relative thereto, said sleeve being slidably mounted on the carriage; cooperating cam members between the sleeve and the carriage; a pawl and ratchet mechanism for moving one of said cam members relative to the other to advance said sleeve relative to the carriage; means mounted on the frame for operating said pawl and ratchet mechanism when the carriage is given a pivotal movement; means for locking the knife-bar to the sleeve for simultaneous movement toward and from the carriage; means for releasing said locking means; means operated by said releasing means for returning said cam members to normal position and permitting the return of the sleeve to a predetermined position with relation to the carriage; an end gate for the mandrel; and means operated by opening movement of the end gate to permit removal of the record from the mandrel for operating said releasing means.
38. In a record-resurfacing machine, the combination of a record to be resurfaced; a record-engaging tool; means for setting the tool in operative position with relation to the record; separately operable finishing cut controlling means; and means operable automatically as an incident to the act of removing a record to return said finishing cut controlling means to inoperative position.
39. In a record-resurfacing machine, the combination of a record to be resurfaced; a settable record-engaging tool; separately operable finishing-cut controlling means; and means for automatically cooperatively releasing the settable record-engaging tool and the separately operable finishing cut controlling means incidental to the operation of removing a record from the machine.
- Signed at Bridgeport, in the county of Fairfield, and State of Connecticut, this 26th day of April, 1927.
